(57) **CLAIM**

The ornamental design for a pest trap, as shown and described.

DESCRIPTION

FIG. 1 is a perspective view of a pest trap showing my new design;

FIG. 2 is a bottom plan view thereof

FIG. 3 is a top plan view thereof

FIG. 4 is a front elevational view thereof; and,

FIG. 5 is a right or left side elevational view thereof.

The rear elevational view is a mirror image of the front elevational view, and the left side elevational view is a mirror image of the right side elevational view.

The broken lines shown in the drawing illustrating unclaimed environmental structures form no part of the claimed design.
